F. P. BUDD

SHOE POLISH CONTAINER

Filed May 27, 1922

INVENTOR

INVENTOR
Frank P. Budd.

UNITED STATES PATENT OFFICE.

FRANK P. BUDD, OF BONESTEEL, SOUTH DAKOTA.

SHOE-POLISH CONTAINER.

Application filed May 27, 1922. Serial No. 564,012.

To all whom it may concern:

Be it known that I, FRANK P. BUDD, a citizen of the United States, residing at Bonesteel, in the county of Gregory and

5 State of South Dakota, have invented certain new and useful Improvements in Shoe-Polish Containers, of which the following is a specification.

This invention relates to containers especially adapted for the reception of polish and other pastes.

In the shoe polish containers now widely in use the opening key is supported by means of a tongue bent up from the edge of the 15 cover and as the result of continued opening of the can this tongue is bent out of place and consequently the key is dislocated. This prevents the key from being flatly engaged with the annular flange surrounding the bottom section of the container and consequently the cap or cover cannot be readily removed.

It is therefore an object of this invention to provide a container of the class described 25 wherein the upwardly directed tongue of the cover is provided with an inwardly directed extension which engages the top and thereby limits the inward movement of the tongue and the key so that the key will be 30 maintained in its proper position with respect to the rib of the lower section of the container.

A further object is to provide a can 35 opener of the class described which is of highly simplified construction, neat in appearance and extremely cheap to manufacture.

Other objects and advantages of the invention will be apparent during the course 40 of the following description.

In the accompanying drawing, forming a part of this application and in which like numerals are employed to designate like parts throughout the same,

45 Figure 1 is a perspective of a can or container constructed in accordance with this invention.

Figure 2 is a detail vertical sectional view through the same.

50 Figure 3 is a fragmentary perspective illustrating the cover and the key.

In the drawing wherein for the purpose of illustration is shown a preferred embodiment of the invention the numeral 5 designates the 55 bottom or lower section of a container for polish or the like, and as illustrated in Fig-

ures 1 and 2 the side of the container is provided with a rib 6 which is engaged by the key so as to facilitate the removal of the upper section or cap 8.

As illustrated in Figure 3 the cap 8 is provided with a side wall 9 having an integral tongue generally designated by the numeral 10 and extended out from the lower edge thereof. In carrying out the invention the tongue 10 is bent upwardly along the line 11 so as to provide an upwardly and outwardly directed attaching portion 12 to which the key 13 is pivotally connected. The terminal portion of the tongue is bent inwardly along the line 15 so as to provide a stop element or holding member 16, which as illustrated in Figure 2 extends inwardly into engagement with the side wall 9 at a point spaced upwardly from its lower edge.

When the key 13 is rotated by the finger piece 19 the lugs 20 will be engaged with the rib 6 so that the cover will be elevated. By reason of the inwardly directed stop element 16 the inward movement of the attaching portion 12 is positively limited and the period of usefulness of the key is greatly increased thereby. By the use of the inwardly directed extension 16 the tongue is not broken off at its point of connection 85 with the cap or cover 8 and as the inwardly directed extension 16 does not increase the cost of manufacture its use is rendered extremely desirable.

I claim:—

1. The combination of a can, a cover therefore, a tongue formed integrally with the cover and inclusive of upwardly and inwardly directed portions, and a key carried by the upwardly directed portion of said tongue 95 and constituting a means to elevate the cover, the inwardly directed portion of said tongue being adapted to contact with the side of the cover, whereby to limit the inward movement of the key.

2. The combination of a can closure having a side wall provided with an integral tongue formed with upwardly and inwardly directed portions, the inwardly directed portion of said tongue being adapted to contact with the side of the closure for limiting the inward movement of the tongue, and a key carried by said upwardly directed portion and being pivoted thereto.

3. In a can, the combination of upper and lower sections, the upper section being provided with a side wall having its edge pro-

vided with an elongated integral tongue, said tongue being extended upwardly and outwardly at an angle to the side of the upper section, and a key pivoted to the upwardly and outwardly directed portion of said tongue and having its ends formed with lugs forming a means to engage the lower section to elevate the upper section, the terminal portion of said tongue being 10 bent inwardly and contacting with the side

of the upper section and limiting the inward movement of the key, said key being provided with a finger grip.

In testimony whereof, I have affixed my signature in the presence of two witnesses. 15

FRANK P. BUDD.
